UNITED STATES PATENT OFFICE.

VINCENT G. ANDERSON, OF THIEF RIVER FALLS, MINNESOTA, ASSIGNOR TO
FREDERICK C. AUSTIN, OF CHICAGO, ILLINOIS.

PROPELLED APPARATUS.

1,270,763.

Specification of Letters Patent.

Patented July 2, 1918.

Application filed May 7, 1917. Serial No. 167,052.

To all whom it may concern:

Be it known that I, VINCENT G. ANDERSON, a citizen of the United States of America, and resident of Thief River Falls, Pennington county, Minnesota, have invented a certain new and useful Improvement in Propelling Apparatus, of which the following is a specification.

My invention relates to propelling apparatus of that kind in which a heavy body, such as that of an ordinary excavating machine, is pulled forward, in an intermittent or step-by-step manner, by partially raising the body on a frame which slides on the ground, so that the body moves forward while the weight thereof, at least in part, is sustained by rollers suitably supported on said frame, and whereby the body and frame alternately move forward, the sliding frame being pulled forward while the body is stationary and resting on the ground.

Generally stated, the object of my invention is to provide a novel and improved propelling apparatus of the foregoing general character.

A special object is to provide an improved construction and arrangement whereby a pull of the cable, when the excavator or other heavy body is moved forward, will be communicated directly to the base of the sliding frame, after the body is slightly raised, thereby to reduce the strain on certain other parts of the apparatus.

Another object is to provide an improved construction and arrangement whereby the sliding frame, when the latter is to be moved forward, will be raised to some extent, so that the weight of this sliding frame, at least in part, will be sustained by the excavator or other heavy body, thus facilitating the forward movement of the sliding frame preliminary to another forward movement of the excavator or other body.

It is also an object to provide certain details and features of construction and combinations tending to increase the general efficiency of a propelling apparatus (commonly referred to as a walking structure) of this particular character.

To the foregoing and other useful ends, my invention consists in matters hereinafter set forth and claimed.

In the accompanying drawings:—

Figure 1 is a side elevation of a propelling apparatus embodying the principles of my

invention, showing the condition of the apparatus immediately after the forward movement of the sliding frame.

Fig. 2 is a similar view, but showing the condition of the apparatus immediately after the forward movement of the excavator-body or other heavy frame to be moved.

Fig. 3 is a plan of the apparatus shown in Fig. 1.

Fig. 4 is an enlarged detail view of the hoisting mechanism by which the heavy body is raised a distance above the ground, or enough to shift the weight thereof onto the sliding frame, showing the parts in the positions in which they are shown in Fig. 1.

Fig. 5 is a section on line 5—5 in Fig. 4. As thus illustrated, my invention comprises an excavator-body-frame A of any suitable character, the excavating apparatus being omitted for convenience of illustration. This body is provided with front and rear shoes or sled-runners B and C, one at each corner of the rectangular frame (see Fig. 3), and it is upon these that the body slides forward upon the ground.

The sliding frame D (there are two of these sliding frames—one at each side of the excavator) comprises the front and rear uprights 1 and 2, which are inclined to bring their upper ends together, and are mounted upon a shoe or sled-runner d which slides on the ground. The uprights 1 and 2 slide forward in a horizontal guide-way E (one at each side of the excavator) provided in the side of the body-frame A, whereby the sliding frame is held upright. A carrier F slides up and down on each frame D, this carrier being provided with supporting rollers f which engage the under side of the body-frame A, to support the latter, and with a roller 3 which engages the forward side of the upright 2, in a manner that will be readily understood. The rear end of the carrier F is provided with a sheave 4, and a cable 5 passes under this sheave and upward and over the sheave 6, which latter is mounted on the rear end of a lever 7 which is pivoted at 8 upon the upright 2, a pivoted link 9 connecting the forward end of this lever with the front end of the carrier F, whereby said lever is operative to raise said carrier when a pull is exerted on said cable.

For this purpose, it will be seen, the cable 5 has one end set

cured to the ring 10 and its other end secured to the pivoted element 11 which swings on the axis of the sheave 4, whereby the carrier F is not only raised by the link 9, but also by the cable 5 when the ring 10 is pulled toward the rear end of the excavator. A cable 12 has one end secured to the ring 10, and then extends rearward and around the sheave 13 on the rear end of the 10 excavator-body, then across and around the sheave 14 on said body-frame, then around the sheave 15, around a sheave 16 on the body-frame, around another sheave 17 on the body-frame, (the sheaves 13 and 17 are 15 mounted at the opposite rear corners of the body-frame), and the other end of this cable is then finally attached to the ring 18 at the other side of the excavator, it being observed that this ring 18 corresponds to 20 the ring 10 previously described, so that the cable 12 forms a connecting link between the two sliding frames. The sheave 15 is mounted on a block 19, and the latter is provided with a sheave 20 for the operating 25 cable 21, the latter having one end secured to the body-frame at 22 and having its other end portion wound on the drum 23, whereby rotation of this drum will tighten the cable 21 and cause a tightening of the 30 cable 12, the sheave 15 acting as an equalizing device, so that the pull on the cable 12 will be communicated equally to the two sliding frames. The cable 12 is provided with a hitch 24 extending from the ring 35 10 to the eye-bolt 25 at the base of the frame D, and the ring 18 has a similar hitch to the other sliding frame, it being understood that the two sliding frames and the apparatus thereof are exactly alike. The shoe 40 or runner d of the sliding frame is provided on its under side with beveled teeth 45 26 which permit the runner to slide readily forward on the ground, but which cut into the ground and prevent backward movement of said runner. When the cable 12 is tightened, the pull exerted on the cable 5, and the corresponding cable at the other side of the excavator, causes the carrier F to rise, thus lifting the forward portion of 50 the body-frame A, so that the weight is either entirely or partly removed from the front runners B, leaving only the rear end of the body-frame resting on the ground. The operation of the cable 12 55 finally straightens out the hitch 24, and the corresponding hitch at the other side of the excavator, until the pull exerted by the winding drum 23 on the cable 12 is communicated directly to the eye-bolt 25, 60 and the corresponding eye-bolt at the other side of the excavator, so that the pull by which the excavator-body-frame is moved forward is ultimately exerted directly on the two sliding frames at the base thereof. 65 In this way, the initial pull on the cable

12 is translated into a powerful lifting effect on the part of the carrier F, and as soon as the slack in the hitch 24 is taken up, in a manner that will be readily understood (see Fig. 2), the pull on this cable 12 is then 70 communicated directly to the base of the sliding frame D, at each side of the body-frame A, with the result that the entire excavator slides forward on the rollers f, while the two frames D stand still. It is at 75 this time that the teeth 26 are of advantage, inasmuch as these teeth sink into the ground and, with the weight of the body-frame supported very largely by the two sliding frames D, thus prevent said frames D from 80 moving backward while the excavator-body A is sliding forward.

The front end of each carrier F has attached thereto a cable 27 which extends downward and around the sheave 28 on the 85 shoe d, and which is then secured to the ring 29, which latter is also connected by a short hitch 30 with the eye-bolt 31 secured in the fitting 32 by which the upright 1 is secured to the runner d, a small sheave 32 being 90 mounted on said fitting to support the cable 27, in a manner that will be readily understood. A cable 33 is attached to the rings 29, at opposite sides of the excavator, and extends around the sheaves 34 and 35 at the 95 front corners of the body-frame A, around the two sheaves 36 at the front of the body-frame, and around the sheave 37 near the center of the body-frame, whereby a tightening of this cable 33 will exert a forward pull 100 on the rings 29, resulting in a lifting of the sliding frames D, followed by a straightening-out or taking-up of the slack of the two hitches 30, whereby the latter then exert a direct forward pull on the front ends of the 105 shoes or runners d, thereby to pull the latter forward at a time when the weight of the two frames D is supported, to some extent at least, by the body-frame of the excavator. The sheave 37 is mounted on a block 38 110 provided with a sheave 39, and a cable 40 has one end thereof secured to the body-frame at 41, and extends around the sheave 39 and back to the winding drum 42, whereby rotation of the latter in a direction to 115 wind the cable 40 thereon will exert a pull on the cable 33, causing the latter to equalize the forward pull on the sliding frames D, so that the latter move forward in the desired manner. With this arrangement, therefore, the tightening of the cable 33 to pull the sliding frames D forward, preliminary to another forward movement of the body-frame A, serves also to lift the frames D, either wholly or partly, and in this way 120 the forward movement of the frames D is made easier. In other words, when the body-frame A moves forward, it is supported by the frames D, to some extent at least, and when the frames D move forward they 125 130

are supported more or less by the body-frame A, the carriers F serving in both cases to transfer at least some of the weight from the moving structure to the stationary structure, so that the two structures take turns at supporting each other and moving forward. By this is meant, of course, that at least some of the weight of the moving structure is sustained by the stationary structure, at least enough to very materially reduce the direct pressure of the moving structure on the ground; and, if desired, the apparatus can be arranged and operated to lift either structure entirely off the ground while it is moving forward.

Thus the propelling apparatus, like others of this general type, has a sort of walking motion when in action as the main body-frame and the sliding frames take turns at moving ahead, and each structure while moving ahead is supported more or less by the other, through the medium of the carriers F, the latter sliding on the guides E when they support the frames D, and the guides E sliding forward in the carriers F when the main body-frame A moves forward.

What I claim as my invention is:—

1. In a propelling apparatus in which a main frame and an auxiliary frame alternately move forward, instrumentalities supported by the auxiliary frame to lift the main frame, when it is desired to move the main frame forward, and means connected with the auxiliary frame adjacent to the base thereof for exerting a backward pull thereon when said instrumentalities are operated to pull the main frame forward.

2. The said structure, as specified in claim 1, in which said means includes a flexible connection which is slack during the initial operation of said instrumentalities, but which connection is straightened out and tightened by the tension of said operation.

3. The said structure, as specified in claim 1, in which said instrumentalities include an operating cable extending forward from the rear portion of the main frame, and in which said means includes a flexible hitch between said cable and the auxiliary frame.

4. The said structure, as specified in claim 1, in which said instrumentalities comprise a carrier in which the main frame slides forward, a cable and sheaves arranged to support said carrier on the auxiliary frame, and in which said means includes a hitch to said cable.

5. The said structure, as specified in claim 1, in which said instrumentalities comprise a tilting lever pivoted on the auxiliary frame, a sheave on one end of said lever, a carrier in which the main frame slides for-

ward, a sheave on said carrier, an operating cable arranged on said sheaves, and a lifting connection between said carrier and the other end of said lever.

65

6. In a propelling apparatus in which a main frame and an auxiliary frame alternately move forward, instrumentalities supported by the auxiliary frame to lift the main frame, when it is desired to move the main frame forward, and means connected with said instrumentalities to lift the auxiliary frame, while the main frame is standing still, so that the auxiliary frame will move forward with more or less of the weight thereof imposed on the main frame.

7. The said structure, as specified in claim 6, in which said instrumentalities comprise a carrier on which the main frame slides forward, with devices to support the carrier on the auxiliary frame, and in which said means include a sheave on the base of said auxiliary frame, an operating connection extending rearward and under said sheave and upward to said carrier, so that a forward pull on said connection serves to lift the auxiliary frame, and a hitch between said connection and the auxiliary frame, whereby the initial operation of said connection to lift the auxiliary frame is followed by a direct forward pull thereon.

8. The said structure, as specified in claim 6, in which said means include a connection for exerting a forward pull on the base of said auxiliary frame, and a connection to exert an upward pull on said auxiliary frame.

9. In a propelling apparatus in which a main frame and an auxiliary frame alternately move forward, instrumentalities supported by the auxiliary frame to lift the main frame, when it is desired to move the main frame forward, comprising a tilting lever pivoted on the auxiliary frame, a sheave on one end of said lever, a carrier in which the main frame slides forward, a sheave on said carrier, an operating cable arranged on said sheaves, and a lifting connection between said carrier and the other end of said lever.

100

10. The said structure, as specified in claim 6, said instrumentalities comprising a tilting lever pivoted on the auxiliary frame, a sheave on one end of said lever, a carrier in which the main frame slides forward, a sheave on said carrier, an operating cable arranged on said sheaves, and a lifting connection between said carrier and the other end of said lever.

105

Signed by me at Chicago, Illinois, this 30th day of April, 1917.

VINCENT G. ANDERSON.

It is hereby certified that in Letters Patent No. 1,270,763, granted July 2, 1918, upon the application of Vincent G. Anderson, of Thief River Falls, Minnesota, for an improvement in "Propelling Apparatus," an error appears in the printed specification requiring correction as follows: Page 1, line 47, after the word "efficiency" insert the words *and desirability*; and that the said Letters Patent should be read with this correction therein that the same may conform to the record of the case in the Patent Office.

Signed and sealed this 30th day of July, A. D., 1918.
